United States Patent Office.

JOHN Y. LANFAIR, OF QUEENSBURY, NEW YORK.

Letters Patent No. 80,638, dated August 4, 1868.

IMPROVEMENT IN WATER-WHEELS.

The Schedule referred to in these Letters Patent and making part of the same.

TO ALL WHOM IT MAY CONCERN:

Be it known that I, JOHN Y. LANFAIR, of Queensbury, in the county of Warren, and State of New York, have invented a new and improved Water-Wheel; and I do hereby declare that the following is a full, clear, and exact description thereof, which will enable those skilled in the art to make and use the same, reference being had to the accompanying drawings, forming part of this specification.

This invention relates to a new and improved water-wheel, of that class which are placed on a vertical shaft, and work within a scroll or curb.

The wheel is designed to be submerged, and is constructed in such a manner that power is obtained from the water, both by impact and reaction.

In the accompanying sheet of drawings—

Figure 1 is a vertical section of my invention, taken in the line *x x*, fig. 2.

Figure 2, a horizontal section of the same, taken in the line *y y*, fig. 1.

Similar letters of reference indicate corresponding parts.

A represents the water-wheel, and

B its shaft.

C is a square wooden base, in the under side of which there is a circular recess to receive the wheel.

D is a square top, between which and the base, C, the curb E is placed, concentric with the wheel, the top and bottom edges of the curb being fitted in annular grooves *a*, made in the under and upper surfaces C D, as shown clearly in fig. 1, the curb and top and bottom being secured together, so as to form perfectly watertight joints, the top, D, and bottom or base, C, being firmly secured, so as to clamp the curb, by means of rods F. The curb E is provided with a gate, G, through which water is admitted within the scroll or curb, and within the latter there are placed two curved throats, H H, the mouths of which are at opposite sides of the centre of the curb.

A tube, H', is at the centre of the bottom or base, C, said tube extending up through the centre of D, and has a cross-piece, I, over it.

This tube admits air to the wheel, and likewise prevents all leakage around the shaft.

The curved throats convey the water to the buckets J of the wheel, which buckets have the parts *b b'*, the former, *b*, being much wider than *b'*, and having such a position as to receive the percussive force of the water at right angles with the direction of the flow of the same, while the bottoms of *b*, as well as the parts *b'* of the buckets, have such an inclination as to receive a power from the water as it escapes from the wheel, by reaction.

The wheel is designed to be of cast iron, and it may be submerged, so as to operate with a good result, the increased head obtained by submersion more than compensating for the power expended in forcing the water through the wheel.

I claim as new, and desire to secure by Letters Patent—

The wheel A, constructed or cast with buckets J, having two parts, *b b'*, arranged as shown in combination with the curved throats H H, all arranged substantially as and for the purpose specified.

JOHN Y. LANFAIR.
